The ornamental design for a hanger nail for wall-mounted articles, as shown and described.

DESCRIPTION

FIG. 1 is a front perspective view of a hanger nail for wall-mounted articles showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a bottom plan view thereof.

The surface shading lines on the claimed portion are provided only to indicate the contour or curvature of the surfaces. They do not indicate color, texture, markings, indicia, graphic representations, surface treatment, or any other ornamentation applied to the hanger nail.
